FREDERICK G. CRANE, OF DALTON, MASSACHUSETTS.

MAGAZINE CATCH AND RELEASE.

1,405,685.

Specification of Letters Patent. Patented Feb. 7, 1922.

Application filed August 8, 1918. Serial No. 248,981.

To all whom it may concern:

Be it known that I, GRANT HAMMOND, a citizen of the United States, residing at New Haven, in the county of New Haven 5 and State of Connecticut, have invented a new and Improved Magazine Catch and Release, of which the following is a specification.

My invention relates to that class of devices employed for holding a magazine in place in an automatic firearm, and for releasing the magazine to permit it to be ejected from the firearm, and an object of 10 my invention, among others, is to provide a device of this class that shall be extremely simple in construction, effective in operation, and that shall be particularly durable.

One form of firearm embodying my invention, and in the construction and use of which the objects herein set out, as well as others, may be attained, is illustrated in the accompanying drawing, in which—

Figure 1 is a view in side elevation 25 of a firearm embodying my invention, with parts broken away to show construction.

Figure 2 is a view in cross section through the frame on the plane denoted by dotted line 2—2 of Figure 1.

Figure 3 is a detail view in vertical section through the receiver and frame on the plane denoted by dotted line 3—3 of Figure 1.

Figure 4 is a top plan view of the magazine.

Figures 5 and 6 are edge and side views of the same.

Figure 7 is a detail view, scale enlarged, of the magazine releasing means.

My invention illustrated and described herein has to do particularly with the magazine that is supported in the handle of the firearm, and with a small portion of the receiver that is located in sliding contact

45 with the upper edge of the frame including said handle, and for this reason the frame or handle and a small portion of the receiver are illustrated in detail herein, as the operation of the device will be readily understood from such showing by those skilled in the art. In said drawings the frame includes a handle 5 of any usual form and construction with a trigger guard 6 at the front end of the frame. Lips 7 are formed on

opposite sides of the upper edge of the frame providing grooves 8 in which lips on the lower edge of the receiver 9 are located, the receiver thus being slidably attached to the frame. As will be readily understood by those skilled in the art forces generated by the explosion of cartridges in firearms are exerted to move the receiver 60 backwardly on the frame independently thereof and to a limited extent, this for the purpose of unlocking the breech-bolt, 65 and any ordinary means will be employed for limiting this backward movement of the receiver on the breech-bolt.

A magazine chamber 10 extends lengthwise of the handle to receive a magazine 11, 70 that is inserted in the handle from the lower end thereof. A magazine retaining pin 12 extends across the handle and across the front edge of the magazine chamber, this pin having a magazine catch 13 to engage a retaining notch 14 in the side of the magazine. A retaining spring 15 forces the catch into engagement with said retaining notch.

A magazine releasing lever 16 is pivotally 80 mounted in a recess in the frame at one side of the magazine chamber, the edge of this lever being beveled to form a magazine releasing cam 17 that engages a magazine releasing notch 18 in the side of the retaining 85 pin 12.

A magazine releasing slide 19 is supported for sliding movement in the lever 16, in the structure shown herein this slide having beveled edges fitting a dove-tailed shaped 90 slot extending through the lever. A slide retaining pin 20 is secured in the lever and projects across said slot and into an elongated notch in the side of the slide to hold the latter in position but to permit a limited 95 lengthwise movement thereof in the lever. A slot 21 is formed through the slide to receive a spring 22 that is seated against one end of the slot to force the slide in one direction. The opposite end of the spring 100 thrusts against a sleeve 23 through which a guide rod 24 extends, this rod extending into a recess 25 in the lower edge of the lever 16 and also through a hole in the end of the magazine releasing slide. This 105 rod may be held in place in the slide in any suitable manner.

The slide 19 has a positioning lug 26 pro-

jecting from one side to engage a position-
ing cam 27 on the upper end of the maga-
zine 11. The follower 28 in the magazine
is seated upon a follower spring 29 in a
5 manner common to magazines of this type
of firearms. Said follower has a slide set-
ting shoulder 30 to engage the lug 26 and
thereby move the end of the magazine re-
taining slide upwardly into the path of
10 movement of the receiver, this, however,
only when the follower completes its up-
ward movement after the last cartridge in
the magazine has been forced into the breech
in the barrel of the firearm.

15 The engaging parts of the retaining pin
12 and lever 16 are preferably beveled so
that said parts may be automatically disen-
gaged, and this disengaging action will be
aided by the force of the retaining spring 15.
20 When thus constructed said retaining pin
will remain in its disengaging position only
momentarily. The catch 13 is beveled so
that when a magazine is inserted in its
chamber its edge engaging said beveled sur-
25 face will force the pin backward until the
catch is opposite the opening 14 when the
spring will snap the catch into holding posi-
tion. Upon such insertion of the magazine
the shoulder cam 27 will engage the position-
30 ing lug 26 and swing the lever 16 from en-
gagement with the releasing notch 18, the
parts being thus positively disconnected.

As the firing proceeds the follower will be
gradually moved upwardly as the cartridges
35 are fed one by one into the breech of the
barrel. When the last cartridge is forced
into the barrel, the follower completes its
movement engaging its slide setting shoulder
30 with the lug 26, thus moving the slide
40 with its upper end into the recess 32 and in
the path of movement of the receiver. When
the last cartridge is fired, the receiver, mov-
ing backwardly a slight distance, carries the
end of the slide with it and this operation
45 rocks the lever 16 on its pivot, forcing the
releasing cam 17 into the notch in the pin
12 and moving the latter to release the maga-
zine. At this time the follower 28 rises a
50 slight distance but not far enough to touch
the lips 31 on the magazine, and the pres-
sure of the follower spring 29 forces the
follower against the lug 26. The slide car-
rying the lug being held from upward move-
55 ment and the follower, therefore, being at
the upward limit of its play the force of the
follower spring is exerted against the bot-
tom of the magazine to eject it, the force of
said spring being greater than that of the
spring 22.

60 In some cases it may be desired that the
magazine shall not be completely ejected
from its chamber in the handle, and I, there-
fore, provide means for retaining the maga-
zine after it has been partially removed. In
65 the structure shown herein a tit 33 projects

from the side of the magazine in position to
engage an edge 34 of an opening in the side
of the handle. The spring qualities of the
engaging parts will be such that the tit may
be disengaged from the edge by the exertion 70
of a little force upon the magazine to re-
move it.

In accordance with the provisions of the
patent statutes, I have described herein the
principles of operation of my invention, to-
gether with the device which I now con-
sider to represent the best embodiment
thereof; but I desire to have it understood
that the device shown is only illustrative
and that the invention may be carried out 80
by other means.

I claim:

1. A firearm including a frame, a receiver
movably mounted on the frame, a magazine
removably mounted in the frame, a manu-
ally operated member for retaining the
magazine in place, automatically operated
means for actuating said manually operated
member to release the magazine, and means
for effecting operation of said parts in the 85
backward movement of the receiver after the
last cartridge has been fired.

2. A firearm including a frame, a maga-
zine removably mounted in the frame, a
manually operated retaining pin to hold the 90
magazine in place, a magazine releasing
lever to operate said pin, and automatically
operated means for actuating said lever to
release the magazine.

3. A firearm including a frame, a maga-
zine removably mounted in the frame, a
member to retain the magazine in place, a
receiver movably mounted on the frame, and
a connection between said receiver and retain-
ing member to operate the latter to release 100
the magazine by reason of movement of the
receiver.

4. A firearm including a frame, a maga-
zine removably located in the frame, a mem-
ber for retaining the magazine in place, a 110
receiver movably mounted on the frame, an
actuating member to be operated by the
movement of the receiver, and an operative
connection between said actuating member
and magazine retaining member.

5. A firearm including a frame, a receiver
movably mounted on the frame, a magazine
removably located in the frame, a manually
operated member to retain the magazine in
place, a lever to engage said member to op-
erate it to release the magazine, means for 120
automatically actuating said lever, and
means for effecting operation of said lever
through the backward movement of the re-
ceiver after the last cartridge has been fired.

6. A firearm including a frame, a maga-
zine removably mounted in the frame, a
manually operating member for retaining
the magazine in place, a lever mounted in
the frame to engage said member to operate 130

it to release the magazine, a receiver mov-
ably mounted on the frame, and a connection
between said lever and receiver to operate
the lever by reason of movement of the re-
5 ceiver.

7. A firearm including a frame, a maga-
zine removably mounted in the frame, means
for retaining the magazine in place, a lever
operatively connected with said means, a
10 slide mounted in said lever, and means for
actuating said slide to cause release of the
magazine.

8. A firearm including a frame, a maga-
zine removably mounted in the frame, means
15 for retaining the magazine in place, a lever
pivotally mounted in the frame, a slide
mounted in said lever, and a receiver mov-
ably mounted on the frame to engage said
slide to effect release of the magazine.

20 9. A firearm including a frame, a maga-
zine removably mounted in the frame, a
magazine retaining pin, a lever pivotally
mounted in the frame to actuate said pin to
release the magazine, a slide mounted in said
25 lever, and a receiver movably mounted on
the frame to engage said slide to actuate it.

10. A firearm including a frame, a maga-
zine removably mounted in the frame, a
member to retain the magazine in place, re-
30 leasing mechanism including a slide opera-
tively connected with said member, and
means for connecting said slide with the fol-
lower of a magazine to subject said slide to
the pressure of the follower spring and
35 thereby to effect movement of the magazine
by the action of said follower spring.

11. A firearm including a frame, a maga-
zine removably mounted in the frame, a re-
taining member for said magazine, and re-
40 leasing mechanism including a slide opera-
tively connected with said retaining mem-

ber, means on the slide to engage a magazine
to position the slide, a follower to engage
said slide, means to hold the slide in position
to receive the force of the follower spring, 45
and means for actuating the slide to release
the magazine.

12. A firearm including a frame, a maga-
zine removably mounted in the frame, a re-
taining pin for said magazine, and releasing 50
mechanism including a slide, a lug on said
slide to engage said magazine, a follower in
the magazine to set the slide in the path of
movement of the receiver, and a receiver
movably mounted on the frame to operate 55
said slide.

13. A firearm including a frame, a maga-
zine removably mounted on the frame, a
member to retain said magazine in place, a
lever to operate said member, a slide mount-
60 ed in said lever, a lug on the slide to engage
said magazine, a follower in the magazine to
engage said lug and set the slide in the path
of movement of a receiver, and a receiver
slidably mounted on the frame to engage 65
said slide to operate it to release the maga-
zine.

14. A firearm including a frame, a re-
ceiver movably mounted on the frame, a
magazine removably mounted in the frame, 70
a manually operated member for retaining
the magazine in place, a lever to engage said
member to operate it, a member movably
mounted on said lever to be projected into
the path of movement of the receiver for 75
actuation thereby, and means connected with
the magazine to move said member into the
path of movement of the receiver as the last
cartridge from the magazine is being forced
into the barrel.

GRANT HAMMOND.
